UNITED STATES PATENT OFFICE.

JOHN CASEY AND MURRAY S. CHISM, OF PHILADELPHIA, PENNSYLVANIA.

DESIGN FOR AN EYEGLASS OR SPECTACLE CASE.

SPECIFICATION forming part of Design No. 25,638, dated June 16, 1896.

Application filed April 16, 1896. Serial No. 587,867. Term of patent 7 years.

To all whom it may concern:

Be it known that we, JOHN CASEY and MURRAY S. CHISM, citizens of the United States, residing in the city and county of Philadelphia, State of Pennsylvania, have invented and produced a new and original Design for Eyeglass or Spectacle Cases, of which the following is a specification, reference being had to the accompanying drawings, forming part thereof.

The leading feature of our design for an eyeglass and spectacle case is the form or shape of one section thereof with a top curved upwardly in longitudinal and transverse directions, and that of the other section with a flat bottom and convex rim.

Figure 1 represents a front view of a case embodying our invention. Fig. 2 represents a transverse section thereof.

Similar letters of reference indicate corresponding parts in both figures.

In the drawings, A and B designate the two sections of the case, the same being connected, as at C, as a hinge. The surface of the section A curves upwardly in longitudinal ²⁵ direction from the end *a* to the end *b*, and in transverse direction from the side *c* to the side *d*, said ends being rounded, and said sides straight, or comparatively straight and parallel. The section B has a flat surface *e* ³⁰ and a convex rim *f*, its sides and ends corresponding with those of the section A.

We claim—

The design for an eyeglass and spectacle case, substantially as described and shown. ³⁵

JOHN CASEY,
MURRAY S. CHISM.
